OUTER COAT

Samuel Summer, Albany, N. Y.

Application January 27, 1949, Serial No. 73,083

3 Claims. (Cl. 2-97)

1

This invention relates to outer coats including topcoats, overcoats, and like garments, and particularly to the varieties thereof adapted to be used with detachable inner linings as occasion may require. Coats so adapted have attained considerable vogue, particularly those provided with an inner lining removably attachable by hook fastener means and a single slide fastener capable of being quickly and conveniently manipulated for inserting or removing the liner. Such slide fastener means have various advantages, but their use has heretofore been attended by some disadvantages also. They are commonly applied to the outer coat by a tape carrying part of the fastener which is attached to the inner side of a fly or flap for concealing the same, the flap extending continuously up the facings of the opposed fronts of the coats, over the shoulders and across the back below the collar. Such a flap, with or without the fastener means, involves a loose flap under the collar portion of the coat which often tends to curl out of place and expose any attached fastener means, besides introducing a degree of bulk tending to interfere with the fit and hang of the garment, and being otherwise cumbersome in the handling of the coat.

While, as stated, some wearers prefer a coat with a detachable lining, others prefer to avoid the above objections where only a topcoat is desired without such a lining, thus leading to two lines of demand. From the point of view of the manufacturer and retailer, on the other hand, it is desirable to meet both demands without the necessity, however, of carrying double stocks and there has been an existing need for a suitable coat to solve this problem.

It has been proposed to construct a garment having separate flaps on the opposed fronts provided with hook fasteners and discontinued at the neck portion, with several snap fastener or other means at the neck portion for attaching thereto an extended portion at the top of the detachable lining. Such a construction, however, involves the manipulation of two sets of hook fasteners and several other fastening means at the neck portion of the coat, so as to be tedious and inconvenient and more likely to get out of order than a single continuous hook fastener means operated by a single slide fastener.

One object of the present invention, therefore, is to provide an improved garment of the above character having a more simple, convenient and inexpensive construction.

Another object is the provision of such a garment having no free or exposed flap, hook fastener or other attaching means encumbering the top of the back of a garment intended for use without a detachable lining, but capable of being readily adapted to provide a continuous at-

2

taching flap and hook fastener means for inserting a detachable lining by the quick, easy and convenient operation of a single slide fastener, where the coat is desired for use with a detachable lining.

A further object is to supply a coat having the above advantages and capable of adaptation as described, with a minimum of alteration of its appearance and construction and with minimum expense.

To these and other ends the invention resides in certain improvements and combinations of parts, all as will be hereinafter more fully described, the novel features being pointed out in the claims at the end of the specification.

In the drawings:

Fig. 1 is a view of the inside of an outer coat embodying the present invention;

Fig. 2 is a diagrammatic sectional view as seen from the line 2-2 in Fig. 1;

Fig. 3 is a view similar to Fig. 1, but showing the coat adapted for and containing a detachable lining, and

Fig. 4 is a schematic sectional view as seen from the line 4-4 in Fig. 3.

The invention is embodied, in the present instance, by way of illustration, in an outer coat or topcoat comprising opposed fabric fronts, 10 and 11 (Fig. 1) and back portions or yokes, 12 and 13, which may be of customary construction. The opposed fronts are provided with facings, 14 and 15, extending from the bottoms of the fronts upwardly over the shoulders and across the top of the back yokes or neck portion, as usual in such garments. These facings are secured to the fabric fronts by stitching, as 16, along their outer free edges and each facing, adjacent its inwardly disposed edge, is secured to its associated front as by a line or lines of stitching, tape or other known connection, as 17. This connection 17 is spaced from the piped inner free edge 18 of the facing so as to leave a free fly or flap 19 extending substantially continuously from adjacent the bottoms of the fronts, up and across the shoulders and the back yokes, as shown, to provide attachment for a separable lining, as hereafter described.

The coat is made with at least a part lining, indicated generally at 20, comprising front yokes 21 and back yokes 22, connected by shoulder seams, as 23. These back yokes are extended at their tops to provide a flap-like portion 24 extending upwardly over and covering the flap 19 of the facings and detachably secured to the facings at the base of the collar 25, as by lines of stitching 26 of an accessible nature adapted to securely hold the extension 24 in place, but capable of being readily ripped out to free the flap 24 if so desired. When thus sewed in place in 60 the manufacture of the garment, flap 24 covers

and conceals the flap 19 to provide a smooth and unbroken inner lining across the top of the back of the coat, free from loose or unexposed flaps, or other fastening means tending to interfere with the proper fit of the coat, or to form an encumbrance in handling it. The lines of stitching 17 are discontinued where they meet the opposite sides of the flap 24, as shown and for a purpose hereafter described.

The above described construction is further shown schematically in Fig. 2 from which it will be seen that the extension or flap 24 forms a substantially continuous and smooth connection between the back yokes and the collar of the coat. It will be understood, of course, that the coat 15 may include the usual or any suitable canvas, padding, or other interior plies which, for clearer illustration, have been omitted from the drawing.

When the coat is sold to a customer desiring to use it with a detachable inner lining, the coat, as above described, is readily adaptable for such use. To this end, the lines of stitching 26 of the flap extension 24 of the back yokes are ripped out and the extension is inserted under the flap 19 and the facings at the base of the collar and secured in this altered position as by means of lines of stitching 27, which may be of the invisible variety, securing it to the fabric back, as shown in Fig. 3, or to some other interior ply inside the flap 19. This relocation of the back yoke flap 24 exposes the continuous facing flap 19 to the under side of which is stitched the known variety of tape 28 carrying a line of hook fasteners 29 for cooperation with the associated line of hook fasteners 30 on a tape sewn to the free edges of a usual inner lining 31. The coat is thus readily adapted for the attachment and removal of the inner lining by means of the known continuous hook fastener means which is quickly and conveniently operated by a single slide fastener and with a minimum likelihood of derangement in the location or attachment of the parts.

The coat as thus adapted is further illustrated schematically in Fig. 4, showing the flap 19 having stitched thereto, as at 32, the tape 28 of the row of hook fasteners 29 engaged with the cooperating fasteners of the inner lining 31, the back yoke extension 24 being secured as by stitching 21 under the flap 19 as described above. The attaching flap 19 extends over and neatly conceals the hook fastener means as customary in the use of such fasteners.

The invention thus provides a garment such as a topcoat adapted to be manufactured, stocked and sold without any free and bulky attaching flap, or hook fastener, or other securing means at the top of its back, to interfere with its fit or obstruct its handling. At the same time, the construction is such as to be readily provided with the known continuous hook fastener means adapted for operation by a single slide fastener for quickly and conveniently attaching or removing a separable lining. Such adaptation of the coat is readily accomplished by simple alterations requiring minimum changes in the appearance and construction of the coat and at minimum labor and expense. The invention thus makes it practicable for a manufacturer to provide the retailer with a single stock of garments which may be readily adapted by the retailer to meet the preference of each customer as regards the preference of a separable lining.

It will thus be seen that the invention accomplishes its objects and while it has been herein

disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. An outer coat provided with a permanent inner lining for at least the upper portions thereof and with a flap extending substantially continuously from the bottom of the front at one side of said coat inwardly of the free edge thereof upwardly over the shoulders, across the neck portion and down the opposed front of said coat adjacent its bottom, said flap being adapted for the attachment to its under side and to conceal a continuous tape carrying fastening means for a detachable inner coat lining, and said permanent lining having at its top a portion extending over and covering said flap and stitched to the facings of said coat to provide a smooth and unbroken inner lining across the neck portion and between the shoulders thereof, said lining extension being adapted to be detached and stitched in position under said flap to continuously expose the same for attachment thereto of said tape of said fastening means.

2. An outer coat having opposed fronts provided with facings having free inner edges forming a flap extending substantially continuously from adjacent the bottoms of said fronts upwardly around the shoulders and across the neck portion, said flap being adapted for the attachment to its under side and to conceal a substantially continuous tape carrying fastening means for a detachable inner coat lining, said coat having at least a part lining stitched therein under said flap, but with a portion at the top of said inner lining extending over and covering said flap and stitched to said facings to provide a smooth and unbroken inner lining across the neck portion and between the shoulders of said coat, said lining extension being adapted to be detached and stitched in position under said flap to continuously expose the same for attachment thereto of said tape for said fastening means.

3. An outer coat having opposed fronts provided with facings extending from adjacent the bottoms of said fronts continuously up around the shoulders and across the back yokes, said facings having free inner edges spaced from the outer edges of said fronts and forming a flap, extending substantially continuously from adjacent the bottoms of said fronts upwardly over the shoulders and across said back yokes, said flap being adapted for attachment to its under side and to normally conceal a continuous tape carrying slide fastening means for a detachable inner coat lining, said coat having at least a part lining stitched therein and under the said flap but having a portion at the top of said inner lining between the shoulder seams extending over and covering said flap and stitched in position to provide a smooth and unbroken inner lining across the top of said back yokes, said lining extension being adapted to be detached and restitched in position under said flap to continuously expose the same for attachment thereto of said tape of said fastening means.
